UNITED STATES PATENT OFFICE.

ELMER W. GIBBS, OF CANTON, OHIO, ASSIGNOR TO THE GIBBS MANUFACTURING COMPANY, OF CANTON, OHIO, A CORPORATION OF OHIO.

TOY.

1,233,866.

Specification of Letters Patent. Patented July 17, 1917.

Application filed March 22, 1916. Serial No. 85,873.

To all whom it may concern:

Be it known that I, ELMER W. GIBBS, a citizen of the United States, residing at Canton, in the county of Stark and State 5 of Ohio, have invented certain new and useful Improvements in Toys, of which the following is a specification.

The invention relates to swinging or oscillating toys, and the object of the improvement is to provide a pivotal bearing and a swinging support for one or more toy figures for readily starting and continuing the swinging thereof for a considerable length 10 of time, without the use of springs or other 15 actuating or operating attachments or appliances.

Preferred embodiments of the invention are illustrated in the accompanying drawings, forming part hereof, in which—

20 Figure 1 is a perspective view of the improved toy showing a pair of figures mounted on the ends of a seesaw swinging support;

25 Fig. 2, a fragmentary plan view of the pivotal parts;

Fig. 3, a median line section across the pivotal support;

30 Fig. 4, a perspective view of the improved toy, showing a single toy figure on a swinging support;

Fig. 5, a fragmentary plan view of the pivotal support shown in Fig. 4; and

35 Fig. 6, a median line section across the pivotal parts shown in Fig. 4.

Similar numerals refer to similar parts throughout the drawings.

The toy as a whole preferably includes a base plate 1, a pair of standards 2, and a cross bar 3 connecting the tops of the standards; the upper ends 2^a of which standards are preferably offset inward to form the shoulders 3^a on each side.

40 The pivot 4 or 4^a is connected to the upper ends 2^a of the standards, preferably by the loops 5 and 5^a clamped around the same, which loops may rest upon the offset shoulders 3^a of the standards. The pivot 4 or 4^a is preferably made in the form of a vertically disposed thin strip or sheet of metal 45 placed on edge and extending between the upper ends of the standard, to which it is secured by the loops 5 or 5^a which preferably rest upon the offset shoulders 3^a thereon. The upper edge of the pivot may be

beveled, if desired, to form a very thin or 55 sharp pivotal support.

The bearing bracket 6 or 6^a is made of spaced side plates 7 or 7^a connected together by the horizontal yoked plate 8 or 8^a, and in each side plate is provided the inverted V-shaped aperture, the angular apex 9 of which bears upon the thin edge of the pivot, and it is evident that the bearing as a whole is adapted to freely oscillate upon the pivot within the limits imposed by the sides of the 60 V-shaped apertures. The side plate 7 or 7^a of the bracket are preferably connected below the aperture by the bar 10, which serves to retain the bracket upon the pivot plate.

The seesaw support illustrated in Sheet 1 70 of the drawings preferably includes the pendent rods 11 secured above in the tubular sleeve formed in or upon the yoke plate 8 of the bearing bracket and stopped from lateral movement by the tongues 12 provided on the edges of the yoke plate, and having their lower ends 13 bent outwardly and extended in longitudinally diverging directions in the form of an inverted T; on the free ends of which are mounted the toy 80 figures 14 and 14^a which may be made of sheet metal stamped to the form of boy and girl, as shown. These figures may be secured in place by bending the bars directly upward and then downward to form an inverted V-shaped spring standard adapted to be entered upward into the body of the figure and having an enlarged eye on its upper end adapted to be forced through the neck into the head of the figure. 85

90 By thus mounting the figures upon the longitudinally diverging ends of the support, which in turn depends from the pivot bracket, it is evident that the center of gravity of these parts is at a substantial distance 95 below the pivotal bearing, and in view of the thin edge of the pivot, it is evident that the pendent support and the figures thereon, will oscillate as a pendulum, thus causing the figures to swing as on a seesaw, and that 100 when such a motion is once started, it will continue automatically for a substantial period of time.

The swing support illustrated in Sheet 2 105 of the drawings preferably includes the four pendent rods 15 secured above to the lower corners of the side plates of the bearing bracket and connected below to the cor-

ners of the seat 16 upon which is mounted the toy figure 17, which may be of sheet metal stamped in the form of a child. In this embodiment of the invention, it is evident that the swing support and the toy figure thereon will oscillate to and fro as a pendulum whenever it is started, and by reason of the thin pivotal support, will automatically continue such motion for a considerable period of time.

I claim:

1. The combination of a pivot having a thin edge, a bracket having a pair of spaced depending side plates, with inverted V-shaped apertures bearing on the pivot edge and a toy-figure support depending from the bracket.
2. The combination of a pivot having a thin edge, a bracket having an inverted V-shaped aperture bearing on the pivot edge, and a toy figure support carried by the bracket including supporting rods depending from the bracket on opposite sides of the pivot.
3. The combination of a pivot having a thin edge, a bracket having an inverted V-

shaped aperture bearing on the pivot, rods depending from the bracket and diverging in opposite directions, and toy figures mounted on the free ends of the diverging rods.

4. The combination of a pivot having a thin edge, a bracket having an inverted V-shaped aperture bearing on the pivot, an inverted T-support depending from the bracket, and toy figures mounted on the free ends of the support.

5. The combination of a pivot, a bracket bearing on the pivot, an inverted T support depending from the bracket, and toy figures mounted on the free ends of the support.

6. The combination of a base having a pair of upright standards offset at their upper ends to form shoulders, a pivot connected to the standards at their upper ends and resting upon the shoulders, said pivot having a thin upper edge, and a bracket having an inverted V-shaped aperture bearing on the pivot edge, with a toy figure support depending from the bracket.

ELMER W. GIBBS.
